ATTORNEY.

UNITED STATES PATENT OFFICE.

ALVIN S. LYON, OF LOWELL, MASSACHUSETTS.

MIXING-PICKER.

SPECIFICATION forming part of Letters Patent No. 435,147, dated August 26, 1890.

Application filed March 17, 1890. Serial No. 344,176. (No model.)

To all whom it may concern:

Be it known that I, ALVIN S. LYON, a citizen of the United States, residing at Lowell, in the county of Middlesex and Commonwealth of Massachusetts, have invented a certain new and useful Improvement in Mixing-Pickers, of which the following is a specification.

My invention relates to mixing-pickers for mixing together different kinds and qualities of fibers, as cotton and wool or hair and wool; and it consists in the combinations and devices hereinafter described and claimed.

In the accompanying drawings, Figure 1 is a plan of two pickers—such as are used for opening and cleaning wool and worsted—belted to each other and connected to each other by a trunk, through which the fiber passes from the picker first in operation to the second picker, and other trunks, through which the fiber passes to the so-called "gauze-room;" Fig. 2, a side elevation of what is shown in Fig. 1.

In blending or mixing different kinds of fibers—as cotton and wool or wool and hair—it is customary to pass the mixture several times through the same picker, and even then much difficulty is experienced in getting a uniform blending of the component fibers. If the mixing is not properly done, the yarns subsequently made from the mixture will be uneven in diameter and strength and in color, if the fibers are of different colors. Again, in the ordinary process of mixing the fibers, a great deal of time is necessarily expended in passing the mixture through the same machine repeatedly, and the fibers are more or less injured by the repeated operation of the machine.

By the use of the improvement hereinafter described I am enabled thoroughly to mix the fibers at substantially a single operation, although I use two pickers in the operation, using them, however, in such a manner that only a single feeding of the stock is necessary and only a portion of the fibers pass through both machines.

In the drawings, A A' represents two pickers of ordinary construction—such as are used in mixing fibers—arranged, preferably, one behind the other, as shown, each picker being provided with a feed-apron, such feed-aprons

being shown at a a⁰, Fig. 1, and with feed-rolls, one of which is shown at a' in Fig. 1, the shaft of the upper feed-rolls in the two machines having, respectively, gears a² a³ secured thereto and engaged by pinions a⁴ a⁵, secured to band-pulleys a⁶ a⁷ concentrically therewith, said band-pulleys being connected by belts a⁸ a⁹ to other band-pulleys a¹⁰ a¹¹, secured to larger band-pulleys a¹² a¹³ concentrically therewith, said last-named band-pulleys being driven by cross-belts a¹⁴ a¹⁵, connecting them to band-pulleys a¹⁶ a¹⁷ on the main or picker shafts a¹⁸ a¹⁹ of the machine. The picker-shafts a¹⁸ a¹⁹ of the pickers, respectively, are provided with band-pulleys a²⁰ a²¹ fast thereon, and are connected by a belt a²², and the picker-shaft of the picker A is provided with another band-pulley a²³, fast thereon, which is driven by a belt a²⁴ in the usual manner.

All of the parts above named are of the usual construction and operation, except that it is not customary to drive one picker from another.

The picker-cylinders a²⁶ a²⁷ are of the usual construction, consisting of spiders a²⁸ a²⁹ on the picker-shafts, each having the free ends of its spiders or radial arms a³⁰ a³¹ united by bars a³² a³³, on which are arranged teeth a³⁴ a³⁵, which are slightly hooked in the direction in which they travel. The shafts of the picker-cylinders are, as usual, journaled in brackets a³⁶ a³⁷, supported on the sides a³⁸ a³⁹ of the frame, and are covered by bonnets a⁴⁰ a⁴¹ in the usual manner, said bonnets being open at the sides at a⁴² a⁴³, in segments of small circles concentric with the picker-shafts in such a manner as to allow the air to rush into the bonnets to supply the partial vacuum caused by the air being thrown outward by the rapid revolution of the cylinders through trunks B B', which open outward from said bonnets and from curved gratings a⁴⁴ a⁴⁵, which, with said bonnets and with the sides of the frames, form in effect fan-cases, within which the picker-cylinders serve as fans or blowers. The trunk B' leads from picker A' into the so-called "gauze-room" C in the usual manner, said room being of the usual construction and having windows (not shown) covered by a thin or gauzy fabric, which allows the escape of air from said picker

A' through said windows, but prevents the escape of fibers. The trunk B of the picker A which first operates on the fibers, instead of discharging into the gauze-room in the usual manner discharges into a box or hood D, preferably having a backwardly-inclined top d and vertical sides d' , the bottom of said box being the feed-apron of the picker A'. Above the rear end of the trunk B another trunk B² leads out of the box D and extends over the picker A into the gauze-room above the rear end of the trunk B'.

When the machines are operated together, as above described, the heavy masses of partially-opened fibers from the picker A will pass through the trunk B and will fall upon the feed-apron of the second picker A', and by the movement of said apron will be carried through said second picker, while the fibers sufficiently opened by the operation of the first picker A, will be carried from the box D through the trunk B² directly into the gauze-room, because the rear opening of said box D is in itself too small to discharge the blast of air from the trunk B, and besides said rear opening of said box D is choked by the feed-rolls of the picker A' and by the fibers passing between said feed-rolls. The trunks B' B² are arranged one below the other, with their discharge ends b' b^2 in close proximity and at such an angle with each other as to cause the fibers from each of said trunks to strike into the path of the fibers from the other of said trunks, and thus to mix said fibers thoroughly. As far as the lighter fibers are concerned, the trunks B B² and hood D form in effect a single continuous trunk or fiber-passage from the picker A to the gauze-room.

I claim as my invention—

40 1. The combination of two pickers with separate fiber-trunks, one of said trunks discharging from each of said pickers, each trunk

being arranged to discharge fibers across the path of the fibers discharged from the other trunk, as and for the purpose specified. 45

2. The combination of two pickers, a fiber-trunk discharging the product of one picker into a feed-box or hood with which the other picker is provided, another trunk discharging the product of said second picker, and a third trunk leading from said hood to discharge the lighter portions of the product of said first picker, as and for the purpose specified. 50

3. The combination of two pickers, a fiber-trunk discharging the product of one picker above a feed-apron with which the other picker is provided, another trunk discharging the product of said second picker, a box or hood arranged above said feed-apron, and a third trunk leading from said hood to discharge the lighter portions of the product of said first picker, as and for the purpose specified. 55

4. The combination of two pickers, a fiber-trunk discharging the product of one picker above a feed-apron with which the other picker is provided, another trunk discharging the product of said second picker, a box or hood arranged above said feed-apron, and a third trunk leading from said hood to discharge the lighter portions of the product of said first picker, the discharge ends of the two trunks last named being arranged to discharge the contents of each trunk across the path of the fibers discharged from the other trunk, as and 60 for the purpose specified. 70

In witness whereof I have signed this specification, in the presence of two attesting witnesses, this 10th day of March, A. D. 1890.

ALVIN S. LYON.
